Primary Examiner — Samantha Wood*Assistant Examiner* — Vanessa Martinez(74) *Attorney, Agent, or Firm* — Bereskin & Parr LLP/S.E.N.C.R.L., s.r.l.; Isis E. Caulder; Justin Philpott(57) **CLAIM**

The ornamental design for a light fixture, as shown and described.

DESCRIPTION

FIG. 1 is a top plan view of a light fixture showing my new design;

FIG. 2 is a bottom plan view thereof;

FIG. 3 is a rear elevation view thereof;

FIG. 4 is a front elevation view thereof;

FIG. 5 is a left side elevation view thereof;

FIG. 6 is a right side elevation view thereof;

FIG. 7 is a top perspective view thereof; and,

FIG. 8 is a bottom perspective view thereof.

The broken lines in the drawings depict portions of the light fixture that form no part of the claimed design. The figures show a symbolic break in the length of the light fixture. The break lines, as well as any portion of the article between the break lines, form no part of the claimed design.
